UNITED STATES PATENT OFFICE.

MICHAEL J. SLOAN, OF BINGHAMTON, AND JOSEPH L. SLOAN, OF ENDICOTT, NEW YORK.

PNEUMATIC UPPER-LEATHER-CUTTING MACHINE.

1,283,341.

Specification of Letters Patent.

Patented Oct. 29, 1918.

Application filed February 8, 1917. Serial No. 147,346.

To all whom it may concern:

Be it known that we, MICHAEL J. SLOAN and JOSEPH L. SLOAN, citizens of the United States, residing at Binghamton and Endicott, respectively, in the county of Broome and State of New York, have invented certain new and useful Improvements in Pneumatic Upper-Leather-Cutting Machines, of which the following is a specification.

10 The present invention relates to cutting and punching machines and has particular reference to a machine for cutting or stamping sheet material, such as leather or the like, more particularly for use in the manu-

15 facture of shoes.

An object of the present invention is to provide a machine of this character which is automatic in operation; which may be controlled by compressed air or the like; which 20 is provided with a plurality of cutters and means for selectively operating the cutters; and to provide the machine with means for automatically removing the blanks when cut and stacking them in their respective piles 25 within a suitable receptacle.

The invention also aims at the provision of means in a machine of this character by which the cutters may be adjusted longitudinally and laterally as well as selectively over 30 the sheet to be stamped for utilizing the entire sheet without waste and so that the cutters may be manipulated to obtain the greatest number of blanks from a sheet of given size.

35 The above, and various other objects and advantages of this invention will be in part described, and in part understood, from the following detailed description of the present preferred embodiment, the same being 40 illustrated in the accompanying drawings, wherein:

Figure 1 is a plan view of a machine constructed according to the present invention.

Fig. 2 is a transverse vertical section taken 45 through the same intermediate the ends thereof.

Fig. 3 is a fragmentary, enlarged section taken vertically and transversely through the operating means, showing one of the 50 cutters in position to be actuated thereby.

Fig. 4 is a fragmentary enlarged section taken through the controlling valve for admitting an actuating fluid to the operating means.

55 Referring to these drawings, the machine in its present embodiment comprises a horizontal frame supported upon legs X, the

frame being arranged over an anvil or support Y adapted to receive a sheet of the material from which the blanks are to be cut. 60

Arranged in one end of the frame is a pair of closely spaced apart guide rods A upon which is supported a carriage comprising the block sections 4 and 5 connected together by rods 6. The blocks 4 and 5 65 carry rollers C bearing on the guide bars A for supporting the carriage and facilitating transverse adjustment thereof relatively to the frame. The block 5 of the carriage carries a depending shaft 8, rotatable in the 70 carriage and carrying upon its lower end beneath the carriage a circular frame or support provided with a circular row of suitably spaced apart plungers 9 mounted for vertical movement through the frame 7 and 75 held normally in raised position by springs 10. The upper ends of the plungers 9 are headed to receive impact of an operating device and to receive the upper ends of the springs 10 therebeneath for supporting the 80 plungers.

The plungers are provided with sprocket wheels 11 arranged thereon preferably below the frame 7, and over which is trained a sprocket chain 16 which may be turned by 85 hand for rotating all of the plungers simultaneously. A sprocket wheel 70 meshes with the chain 16 and is carried on the lower end of a shaft 71 adapted to travel with the carriage. Beveled pinions connect the shaft 71 90 with a hand wheel shaft 72 supported on the cross heads 33, the pinion of the shaft 72 being slidable thereon to follow the carriage. The lower ends of the plungers are provided with cutters in the form of cones 12 of the 95 desired transverse configuration having cutting edges at their lower ends and having therein ejector blocks 13 held extended from the lower ends of the cutters 12 by springs 14 surrounding guide pins 15 connecting the 100 blocks 13 to the plungers.

If desired, counters 40 of any suitable type may be mounted on the frame 7 adjacent the plungers 9 and provided with operating arms 41 lying beneath the heads of 105 the plungers to be actuated thereby when depressed for keeping tally upon the number of operations of the respective plungers.

Extending longitudinally of one of the guide bars A is a shaft 55 suitably mounted in the frame and upon which is keyed a longitudinally slid able beveled gear wheel 54 meshing with a corresponding beveled gear wheel carried upon the carriage block 5 and

which is connected by intermeshing beveled gear wheels 52 and 53 to the frame supporting shaft 8. The shaft 55 has a spur gear wheel 61' near one side of the frame meshing with a correspondingly formed gear wheel 61 mounted on a shaft 57 extending transversely of the frame and mounted in bearings 36 carried on cross heads 33 at the sides of the frame, and which is provided 5 with a thumb wheel 63 on its outer end for manually turning the shaft. A number wheel 62 is preferably mounted upon the shaft 57 near the thumb wheel 63 by means of which the relative positions of the shaft 10 57 may be determined. The numbers on the wheel 62 preferably correspond to the cutters or plungers on the frame, and the cutters may be adjusted into a predetermined position over the anvil Y by turning the 15 shaft 57.

The operating means is carried upon the block 4 of the carriage and is adapted to overhang the anvil Y. The operating means comprises a cylinder 3 rising from 20 the block 4 and provided with a piston 25 therein normally urged toward the upper end of the cylinder by an expansion spring 25. The lower end of the spring 26 encircles an impact pin 27 suitably headed 30 to receive the piston 25 thereagainst, and which is normally urged upward by a spring 28 between the head of the pin and the bottom of the cylinder 3. The pin 27 slidably engages through the block 4 and is adapted 35 to move downwardly therethrough.

The block or carriage also carries a controlling valve in the form of a cylindrical valve casing 21 to one side of which is connected a pipe 20 opening into the top of 40 cylinder 3. The casing 21 has a rotary valve therein with an axial port communicating with a supply pipe Z leading from any suitable source of fluid pressure supply. The rotary valve has a radial port adapted 45 to open into an exhaust pipe 64 which leads downwardly into a position beneath the carriage and adapted to register at one side of the cutter in operative position to deliver a blast of air transversely beneath the cutter 50 and across the anvil Y. The rotary part of the valve 21 carries a bell crank lever on one end to which an adjacent end of a connecting rod 24^a is connected, the opposite end of the rod having pivotal connection 55 with a latch lever 22. The connecting rod is mounted in suitable brackets in the block 4 and is preferably spring tensioned at one end to retain the valve in closed position. To prevent opening of the valve when a 60 cutter is out of line with the operating mechanism the other arm of the bell crank lever has a stop bolt 69 depending therefrom and adapted to engage the upper surface of the frame 7. The frame 7 has an aperture 65 therein opposite each plunger to receive

the stop rod 69 when the adjacent plunger registers beneath the impact pin 27, whereupon the valve may be opened and the apparatus actuated.

The carriage is provided with a handle *a* 70 which may be supported upon a pair of arms 18 converging laterally from the block 4, and which may be supported in an upwardly inclined position by a brace rod 19 arranged between the outer ends of the arms 18 and an intermediate portion of the cylinder 3. The latch rod 22 extends longitudinally of the arms 18 and is connected to a trigger 23 pivoted to the handle *a* so that the trigger 75 may be moved by the finger for actuating the valve 21.

The block 4 of the carriage has pivoted thereto a lever 30, the long arm of the lever extending upwardly and laterally beneath the arms 18 of the handle and being guided 85 and tensioned in its movement toward and from the handle by spring 31 and its guide bolt, and the arm 30 having a latch bar 32 the nose of which is adapted to enter a notch 33^a in the latch bar 22 to lock the valve 90 21 closed.

The transverse shaft 55, used for adjusting the cutters into position over the anvil is connected at its end opposite to that upon which the gear wheel 61' is mounted to a 95 shaft 55' arranged at the side of the frame, by intermeshing beveled gear wheels as shown in Fig. 1, and the shaft 55' is connected by beveled gear wheels 50 and 51 with a shaft 49 which operates a rotatably 100 mounted receptacle or container in which the stacks of blanks cut are adapted to be deposited. The shaft 49 is connected by beveled gear wheels 47 and 48 to a vertical shaft 45 upon which the receptacle 44 is 105 secured. The train of gearing between the shaft 45 of the receptacle and the shaft 37 for adjusting the cutters is so proportioned as to advance the cutter frame 7 and the receptacle simultaneously in predetermined 110 stepped relation so that the blanks cut by one of the cutters are deposited in a pre-determined stack or portion of the receptacle 44. A conveyer 43, preferably in the form of an extensible tube, which may comprise a 115 plurality of telescoping sections as shown, is supported at one end above the receptacle 44 and at its opposite end upon a bracket 42 depending from the carriage to support the mouth of the tube 43 at one side of the 120 cutter in operative position and directly opposite the open end of the exhaust pipe 64. The conveyer tube 43 is adapted to receive the cut blank from the bed plate or anvil Y when the blank is blown into and 125 through the tube by the air exhausting from the pipe 64. The tube 43 is of sectional or flexible construction to admit adjustment of the carriage laterally and longitudinally in the frame, and to convey the blanks from 130

the adjusted position of the carriage to the receptacle 44 which is mounted upon the relatively fixed shaft 45.

The guide rods A have cross heads 33 connecting the opposite ends of the guide rods and projecting rearwardly therebeyond to form bearings for a transverse shaft 37. The shaft 37 carries pinions 39 upon its opposite ends which mesh with rack bars 34 in the sides of the frame. The shaft 37 has a hand wheel 39^a thereon, by means of which the shaft may be turned to adjust the carriage longitudinally in the frame. The cross heads 33 are provided with vertically spaced apart pairs of grooved rollers 35 engaging against the upper and lower sides of the shafts 34 to hold the guide rods A to the frame.

The cross head 33 adjacent the spur gear 20 wheel 61 is provided with a pawl 65 engaging the gear wheel 61 to hold the same from turning in one direction so that the cutter frame 7 and the receptacle 44 may be turned in but one direction. The shaft 57 is provided with a cylindrical portion or drum between the cross heads 33 and the drum has a spiral row of perforations 58 therein adapted to be engaged one at a time by a locking dog 60 slidably mounted in a bracket 59 on the block 4 of the carriage. The dog 60 is yieldingly held against the drum and yieldingly holds the frame 7 and the parts connected thereto in adjusted position.

In operation, a sheet of material is placed 35 upon the anvil Y and the carriage is adjusted longitudinally in the frame by turning the shaft 37, and is adjusted laterally in the frame by operating the handle a, to adjust the operating mechanism over the desired portion of the sheet on the anvil. The shaft 57 is now turned to bring the desired cutter beneath the operating mechanism and the sprocket chain 16 is moved circularly to turn the cutter into the desired angle with respect to the longitudinal axis of the frame. The operator now releases the latch rod 22 and draws the trigger 23 to open the valve 21 and admit compressed air, or other suitable fluid medium, into the upper end of cylinder 3. The air forces the piston 25 down against the impact pin 27, which latter strikes the head of the adjacent plunger 9 and forces the plunger and its cutter 12 downward. As soon as the blank has been 50 cut from the sheet, and the trigger 23 released, the valve 21 is closed by the spring 20 actuated connecting rod 24^a, and the pipe 20 is placed in communication with the exhaust pipe 64. The fluid under pressure of the piston 25 and spring 26 is ejected from the end of the pipe 64 toward the mouth of the conveyer tube 43 with sufficient force to dislodge the blank from the lower end of the cutter and the anvil and force the blank 55 through the tube 43 into the adjacent side

of the receptacle 44. The carriage may now be quickly shifted into another position and the cutting operation repeated. The blanks fed to the receptacle 44 are deposited one on top of the other beneath the outlet end of the conveyer tube. When a different cutter is adjusted into position beneath the operating mechanism the receptacle 44 is correspondingly adjusted to bring the corresponding compartment or stack 46 into position beneath the delivery end of the tube.

It is of course understood that various changes and modifications may be made in the details of construction and design of the above specifically described embodiment of this invention without departing from the spirit thereof, such changes and modifications being restricted only by the scope of the following claims:

What is claimed is:

1. In a blank cutting machine, the combination of a frame, a carriage adjustably mounted in the frame, operating means mounted on the carriage, an anvil arranged beneath the carriage to support a sheet to be cut, means between the carriage and the frame to adjust the carriage into position over the anvil, and a plurality of cutters arranged to be selectively disposed beneath the operating means for actuation thereby.

2. In a blank cutting machine, the combination of a frame, a carriage adjustably mounted in the frame, an anvil arranged beneath the carriage to support a sheet of material, operating means mounted on the carriage, a plurality of adjustable cutters mounted on the carriage for individual adjustment beneath the operating means for actuation thereby, and means for adjusting the angular positions of the cutters with respect to the longitudinal axis of the frame.

3. In a blank cutting machine, the combination of a frame, a pair of guide bars mounted transversely in the frame and adapted for longitudinal adjustment therein, a carriage adjustably mounted on the guide bars, operating mechanism mounted on the carriage, a cutter frame adjustably mounted on the carriage, a plurality of cutters mounted in the cutter frame, means for adjusting the cutter frame to selectively dispose the cutters one at a time beneath the operating mechanism, and means for actuating the operating mechanism when a cutter is brought into register therewith for operating the cutter.

4. In a blank cutting machine, the combination of a frame, a carriage longitudinally and laterally adjustable in the frame, operating means on the carriage, a plurality of cutters adjustably mounted on the carriage, means for moving the cutters selectively, one at a time, into register with the operating means to be actuated thereby, an anvil beneath the carriage to support a sheet of

material, a receptacle mounted on the frame, means connecting the receptacle to the cutters for adjusting the receptacle therewith, and delivery means for removing the cut blank from the anvil to a corresponding portion of the receptacle.

5. In a blank cutting machine, the combination of a frame, a carriage adjustably mounted in the frame, a rotary frame mounted on the carriage, a circular row of cutters mounted on the rotary frame, means for turning the frame to adjust the cutters, a cylinder rising from the carriage, a spring actuated piston in the cylinder normally urged into the upper end of the same, a controlling valve on the carriage, a pipe from the valve to the upper end of the cylinder, a source of fluid supply communicating with the valve, said valve being adapted to be opened to admit fluid to the top of the cylinder for moving the piston down, an impact pin mounted on the carriage beneath the piston to be depressed thereby, and means associated with the valve for freeing the same for operation when a cutter is adjusted into register with said impact pin.

6. In a blank cutting machine, the combination of a frame, a carriage in the frame, a fluid pressure cylinder mounted on the carriage, a controlling valve, a pipe connecting the valve to the cylinder for delivering fluid to the latter when the valve is open, an anvil arranged beneath the carriage adapted to support a sheet to be cut, a cutter for adjustment beneath the fluid cylinder to be actuated by the piston thereof, a receptacle for blanks, a conveyer leading from the anvil to the receptacle, and an exhaust pipe leading from the valve to the anvil and opening toward the conveyer adapted to deliver fluid exhausted from the cylinder into the conveyer for feeding cut blanks thereto.

7. In a blank cutting machine, the combination of a frame, a movable carriage mounted on the frame, a handle on the carriage for adjusting the same, a fluid cylinder on the carriage, a valve on the carriage controlling fluid pressure to the cylinder, a trigger on the handle connected to the valve for operating it, a cutter frame adjustably mounted on the carriage, a plurality of cutters on the cutter frame, means on the carriage for adjusting the cutter frame to selectively register the desired cutter with the fluid cylinder for actuating the cutter, a receptacle mounted on the frame, a connection between the receptacle and the cutter frame for adjusting the receptacle therewith, and means for delivering cut blanks to the receptacle.

8. In a blank cutting machine, the combination of a frame, operating means adjustably mounted on the frame, an anvil be-

neath the operating means for supporting a sheet of material to be cut, a plurality of cutters arranged in the frame for adjustment, one at a time, into line with the operating means, a flexible conveyer tube secured at one end beneath the operating means and adapted to open at one side of a cutter when in operative position, a receptacle fixed to the frame at the opposite end of the conveyer tube, said conveyer tube being adapted to flex during the adjustment of the operating means, and means associated with the operating means for delivering cut blanks from the handle through the conveyer tube into the receptacle.

9. In a blank cutting machine, the combination of a frame, a carriage adjustably mounted in the frame, an anvil fixed beneath the frame adapted to support a sheet of material to be cut, operating means carried by the carriage and including a fluid pressure cylinder, cutters mounted on the carriage for adjustment, one at a time, beneath the operating means, means for adjusting the carriage to dispose the cutter over the desired portion of the anvil, said operating means including an exhaust pipe terminating at one side of the adjusted cutter, a bracket depending from the carriage, a flexible conveyer tube, secured at one end to the bracket, and opening at the opposite side of said cutter, and a receptacle into which said tube discharges, said operating means being adapted to deliver fluid under pressure from the cylinder to said pipe for dislodging a cut blank from beneath the cutter and delivering the blank through said tube into the receptacle.

10. In a blank cutting machine, the combination of a frame, operating means mounted in the frame, a cutter frame adjustably mounted in said first frame, a plurality of cutters mounted on the cutter frame and adapted to be adjusted, one at a time, into position beneath said operating means, an anvil adapted to receive a sheet to be cut, a receptacle having compartments therein corresponding to the number of cutters on the cutter frame, blank feeding means leading from the anvil to the receptacle to deposit blanks in the compartments of the receptacle, one at a time, and a connection between the cutter frame and the receptacle for simultaneously adjusting the same to deliver blanks cut by the cutters into their respective compartments in the receptacle.

In testimony whereof we have affixed our signatures in the presence of two witnesses.

MICHAEL J. SLOAN.
JOSEPH L. SLOAN.
